UNITED STATES PATENT OFFICE.

JOHN BLAIR, OF NEW YORK, N. Y.

CLIP FOR FOUNTAIN-PENS, &c.

No. 909,862.

Specification of Letters Patent.

Patented Jan. 18, 1909.

Application filed May 18, 1908. Serial No. 433,417.

To all whom it may concern:

Be it known that I, JOHN BLAIR, a citizen of the United States, residing at New York city, Brooklyn, county of Kings, State of New York, have invented new and useful Improvements in Clips for Fountain-Pens and Similar Articles, of which the following is a specification.

This invention relates to a clip adapted 10 to engage a fountain pen or similar article, and to secure the same, in a convenient and reliable manner, to the pocket of the wearer.

In the accompanying drawing: Figure 1 is a side view of my improved clip, showing 15 it in engagement with a fountain pen; Fig. 2 a top view of Fig. 1; Fig. 3 a front view of the clip, and Fig. 4 a side view of the clip, showing it in use.

The clip is composed of a continuous 20 length of wire bent to form an open loop and a finger integral with the loop. As shown, the wire is first bent into circular form, as at 10, to form a single open loop, the ends of which are spaced as at 11. The 25 two opposed ends of circular wire-section 10 are then bent downwards as at 12, to form the two shanks of an integral U-shaped finger which joins the loop at an acute angle, (Fig. 1). The finger wire-sections 30 12 are thus also spaced on top, while they are bent towards each other at the bottom and are here surrounded by a tubular sleeve 13. In this way the entire clip is made 35 endless and the loop-section thereof is readily expandible to tightly grasp articles

of different diameters. The finger-section of the clip is convex, as at 14, to form a bearing.

In use, the loop-section of the clip is slipped over a fountain pen or similar 40 article 15, and then the latter is placed into the pocket of a garment 16, in such a way that the finger-section of the clip projects outwardly from the pocket and bears with its convexity against the front flap 17 45 thereof. During this manipulation, the finger-section will be bent outward, (full lines Fig. 4), to an extent corresponding to the thickness of the cloth, so that in this way the loop-section of the clip will be 50 tightened around the fountain pen to securely hold it in position. An upward pull on the fountain pen and clip will readily disengage the latter from the garment, so that the device may be readily withdrawn. 55

I claim:

A device of the character described, comprising an endless wire forming a single loop having opposed spaced ends, and a U-shaped convex finger, the two shanks of 60 which join the two spaced loop-ends at an acute angle to the loop, substantially as specified.

Signed by me at New York city, (Manhattan,) N. Y., this 16th day of May, 1908. 65

JOHN BLAIR.
